UNITED STATES PATENT OFFICE

2,508,835

SAFETY LOCK FOR EXTENSIBLE MASTS

James Moon and John F. Shaw, Altadena, Calif.,
assignors to Western Oil Tool & Engineering
Co. Inc., Glendale, Calif., a corporation of Cali-
fornia

Application June 15, 1946, Serial No. 677,031

4 Claims. (Cl. 254—148)

1

This invention relates to a safety device for a sectional derrick or ladder, mast, or other structure to be erected for purposes of carrying a load to such a structure.

It is quite common to employ such structure in sectional form, one section being adapted to be elevated and carried upon a lower section to vary the height of the structure. It is also common to provide a locking means to hold the elevated section in position on the lower supporting section.

Examples of such structure may be found in the telescoping, portable derrick or mast employed in drilling of oil wells and in operations around producing wells.

Such structures are such as are illustrated in United States Patents Nos. 2,204,713; 2,358,755; and 2,336,432. In such structures the mast is composed of a lower portion which is hinged or otherwise mounted on the vehicle on which it is transported. It may thereafter be erected in an upright position and lowered therefrom onto the vehicle. The upper portion is telescoped within the lower portion when the derrick or mast is in position on the vehicle. After the lower portion is erected, the telescoped upper portion is raised and extended by means of a line which causes the extension of the mast. This line passes over a reel which applies the power for lifting or lowering the upper portion of the derrick or mast. When the derrick or mast is fully extended, various locking means may be employed to hold the derrick or mast in the extended position.

It is not an uncommon experience that the hoisting or elevating line parts or some accident occurs either during the lifting or lowering of the telescoping section when the power goes off or the winch or reel breaks down. The telescoping portion then falls, causing great damage and resulting, in numerous cases, in serious injury to operating personnel.

We have designed and built a safety lock or catch which, whenever slack occurs in the line or the line breaks in such circumstances as to permit the telescoping portion to fall and before such fall occurs, locks the derrick in place. The safety lock of this invention may operate at any position of the telescoping section during its extension or at the limit of extension or during retraction. Our locking mechanism will operate to hold the derrick at any attained position whenever slack on the hoisting line or a break therein occurs, which, except for the presence of our locking device, would cause the telescoping section to fall.

2

These objects and others will be clear to those skilled in the art from a further description of our invention taken together with the drawings, in which

5 Fig. 1 shows a side elevation of a telescoping mast such as is used in portable drilling machines, with the telescoping derrick in partly extended position and with all structural elements not necessary for description of our invention eliminated;

10 Fig. 2 is a front elevation of Fig. 1;

Fig. 3 is a schematic view of the extending line, showing the arrangement of the sheaves;

15 Fig. 4 is a section taken on the line 4—4 of Fig. 2;

Fig. 5 is a detail in part section showing the switch mechanism;

Fig. 6 is a view taken on line 6—6 of Fig. 5;

20 Fig. 7 is a detail showing in part section the wedge lock and showing also schematically the wiring diagram and the switch;

Fig. 8 is a section taken on line 8—8 of Fig. 7; and

Fig. 9 is a view taken on line 9—9 of Fig. 7.

25 The telescoping derrick or mast is composed of a lower section 1 in which telescopes the upper section 3. The lower section 1 is mounted on the truck 2 so that it may, when section 3 is lowered, rest on truck 2, and is lowered onto the truck by pivoting section 1 on a pivot mounting not shown in the drawing. The elevating mechanism and other conventional equipment usually mounted on the truck are omitted for clarity, since they do not form part of this invention.

30 When the derrick is moved to an upright position, it is securely locked in said upright position, as shown in Figs. 1 and 2. The telescoping portion 3 (see Figs. 1, 2, and 4, inclusive) slides inside the lower section 1 with the longitudinal posts 4, 6, or 8 sliding in guides 5 and 7 mounted on 1.

35 In order to lift and lower the telescoping section 3, a cable 8, passing over power reel 9 and sheave 10 mounted on the truck 2, is threaded over sheave 11 mounted on the lower section of 1 and over sheave 12 mounted on the top brace 30 of 1 and over sheaves 13 and 14 mounted on the lower part of the telescoping section of 3 and to a deadhead 15 mounted on the top brace 30.

40 When the line is shortened by winding it upon the reel 9, the section 3 is raised to extend the length of the derrick, and when the line is unreeled the telescoping section descends. Should the line 8 part or should a winch failure or power shut-off occur during the raising or lowering of

3, it will drop, and since it is quite heavy damage or injury may occur.

In order to provide against this eventuality, we have devised a safety catch or lock which will hold the upper section in any position attained by the derrick during lifting or during lowering and will also lock the upper section in position. This will prevent the upper section from dropping when slack occurs in the line either due to the parting of the line or any failure in the hoisting mechanism during lifting or lowering.

As will be recognized, during lowering and extending operations, the line 8 is under tension. We have designed a latch or lock arrangement which engages one or more of the upright leg members of the telescoping section and which lock sets to lock such leg member to the lower section when slack occurs in the line, but which remains in open position to permit the free movement of the upper section so long as tension is maintained on said line.

We accomplish this function by mounting upon the lower member 1 a switch mechanism which is operated to open a circuit whenever slack occurs in the line. When the switch is operated to open the circuit, slips mounted on 1 are set to engage the legs of the section 3 to lock the legs of 3 to the section 1.

Such a switch is illustrated in Figs. 5 and 6. It is composed of a casing 16 in which is mounted a quick-acting switch 17 of which many forms are available on the market, as will be understood by those skilled in this art. The switch is operated by a shaft 18 which is actuated by an arm 19 acting against a spring 20. The rod 22 is pivotally connected to 19 at 21 and may be reciprocated in a bore 23a in the casing 16. Adjusting screws 24, 25, and 23 are provided. The rod 22 is lifted by arm 26 against spring 27 when the arm 28 is moved to the left and spring 27 returns the rod 22 to move the rod 22 downward when the arm 28 moves to the right. When the rod 22 is lifted the arm 19 moves the switch to closed position, and when the rod 22 moves downward the switch is opened. By adjusting nuts 24 and 25, some lost motion of desired amount is permitted in 26 before actuation of the rod 19 occurs.

The switch mechanism 16 is mounted on the lower section 1, at some convenient place, suitably between sheaves 11 and 12 so that the roller bears against the line 8 when the line is in tension. The roller 29 is set against the line so as to raise 26 to place the switch 17 in closed position. The nuts 25 and 24 are adjusted so that the vibration of the line 8 during operation will not trip the switch 17. The motion of arms 28 which will trip the switch, as determined by the settings of 24 and 25, is therefore something in excess of that vibrating movement of 8.

This occurs when slack appears in line 8 or it parts. Then the spring 27 snaps the rod 22 downward to trip the switch.

The tripping of the switch opens a circuit which permits the safety catch to operate. This catch or lock 31 is mounted upon the brace 30 (see Figs. 1 and 2), which is cut out at 32a to fit the curvature of the leg 6 of section 3. The latch consists of a base 32 upon which is mounted a housing 31 and side members 38. The walls 38 are stepped at 39. On steps 39 is mounted a plate 40 having an arcuate portion 41 to fit the curvature of the tubular leg 6 of section 3. The face of the housing 31 is covered by an inclined plate 33 which carries a cut-out slot 37. Within the housing chamber 38 of the housing 31, and mounted on the plate 33, is a pair of electromag-

netic solenoids 34 and 35 connected in parallel.

The armatures of the solenoid are connected to an arm 36 which passes through the slot 37. The rod 43 is screwed into the arm 36 and carries a washer 45, and passes slidably through an appropriate bore 42 of the plate 40. A spring 44 is mounted between the plate 41 and the washer 45. A plurality of wedge dies 50 having an arcuate face to engage the tubular leg 6 are slidably mounted on the wedge 49 which has an arcuate face to accommodate the arcuate steps 50 and a plane back to conform with the face 33. The wedge 49 is mounted on bolt 47 which passes through a bore 46 in the arm 36 and operates against the spring 48.

When the line is in tension the switch is closed to complete the circuit through the solenoids. This causes the armatures to lift arm 36 and wedge 49 against the springs 44 and 48 to move the wedges up the inclined plane of 33 to free the slips 5 from the leg 6 which is then free to move. Should slack or failure of the line 8 cause the switch to operate to open the circuit through the solenoids 34 and 35, the springs 44 and 48 will act to snap the wedge 49 downward down the inclined plane 33 to set the slips 50 against the leg 6 to lock the legs and therefore the section 3 at any attained position, as explained above.

It is to be noted that since this safety measure is desired primarily to function during the limited times that the section 3 is extended or retracted, the switch 16 is set to keep the circuit through the solenoids open until a tension is exerted on the line when the circuit is closed to unlock the wedge lock. When the accident occurs, and against which it is intended to guard, i. e., when slack occurs, the circuit is opened and the wedges set.

While we have described a particular embodiment of our invention for the purpose of illustration, it should be understood that various modifications and adaptations thereof may be made within the spirit of the invention as set forth in the appended claims.

45 We claim as our invention:

1. A safety latching means for a sectional extensible mast comprising a lower mast portion and an upper mast portion, said upper mast portion being carried upon said lower mast portion and extensible or retractible on said lower mast portion by a hoist line, a latch including a base mounted upon said lower portion, an inclined plate mounted on said base, a wedge slidably mounted on said plate, a solenoid, an arm connecting the armature of said solenoid with said wedge, a spring mounted on said arm to oppose the motion of said wedge when the solenoid is energized and to move the wedge in opposite direction when the solenoid is de-energized, 60 a power circuit connected to said solenoid, a switch in said power circuit, said switch being mounted in proximity to said hoist line, said switch including an arm bearing against said line when said line is in tension, a switching mechanism operated by the motion of said arm to control the operation of said solenoid.

2. A safety device for an extensible mast comprising a mast formed of an outer and an inner extensible section, the inner section telescoping 70 into the outer section, means for extending said mast comprising a hoist line connected at one end of said line to the top of said outer section and to a hoist at the other end of said line, a sheave mounted on the lower end of said inner section, said line passing over said sheave where-

by said inner section is extended by shortening of said line by operation of said hoist, a locking means mounted on said mast to lock said extensible section to said outer section at all points during the extension or retraction of said extensible section, and means for setting said lock on occurrence of slack in said line, said setting means comprising an operative connection between said latch and said line, said operative connection being connected to said line at a point in said mast intermediate the point of attachment of said line to the top of said outer section and to said hoist.

3. A safety device for an extensible mast comprising a lower mast section, said lower mast section being composed of upright legs and top and intermediate cross braces, an extensible mast section, said extensible mast section being composed of upright legs and braces therefor, said extensible mast section being adapted to slide over said lower portion during extension or retraction of said extensible mast section, the legs of said lower section being contiguous to complementary legs of said lower portion, a hoist line passing through said mast and connected to an upper brace of said lower portion and to a lower brace of said extensible section and to a hoist, means for extension or retraction of said extensible mast section, a latch mounted on an upper cross brace of said lower portion of said mast to lock the legs of said extensible section to said lower portion, means operatively connected at an intermediate point of said line between said point of connection of said line to the outer section and said hoist for maintaining said latch open when said line is in tension during

said extension and lowering, said means also setting said latch to lock said sections together on appearance of slack in said line.

4. A latch for a sectional, extensible mast, said latch comprising an inclined plate, a wedge slidably mounted on said plate, a solenoid, an arm connected to the armature of said solenoid connecting the armature of said solenoid with said wedge, a spring mounted on said arm to oppose the motion of said wedge when said solenoid is energized and to move said wedge in an opposite direction when the solenoid is de-energized, a power circuit connected to said solenoid, a switch in said power circuit, said switch being adapted to be mounted in proximity to a hoist line for extension of said mast, said switch including an arm adapted to bear against such hoist line when said hoist line is in tension, a switching mechanism operated by the motion of said arm to control the operation of said solenoid.
